US0D1053121S

(12) **United States Design Patent** (10) **Patent No.:** **US D1,053,121 S**
(45) **Date of Patent:** **** Dec. 3, 2024**

(54) **BATTERY PACK**

(71) Applicant: **TOPAK POWER TECHNOLOGY CO., LTD.**, Shenzhen (CN)

(72) Inventors: **Xiaotao Yang**, Shenzhen (CN);
Zhiming Ke, Shenzhen (CN)

(73) Assignee: **TOPAK POWER TECHNOLOGY CO., LTD.**, Shenzhen (CN)

(**) Term: **15 Years**

(21) Appl. No.: **29/860,748**

(22) Filed: **Nov. 22, 2022**

(30) **Foreign Application Priority Data**

Oct. 24, 2022 (CN) 202230702126.9

(51) **LOC (14) Cl.** **13-02**

(52) **U.S. Cl.**

USPC **D13/103**

(58) **Field of Classification Search**

USPC D13/103, 107, 108, 110, 118, 112, 119,
D13/184, 199, 104, 116

CPC H01M 50/103; H01M 2/1072; H01M
2/1022; H01M 10/44; H02J 7/14; H02J
7/025

(57) **CLAIM**

The ornamental design for a battery pack, as shown and described.

DESCRIPTION

FIG. 1 is a front and top perspective view of a battery pack showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1; and,

FIG. 10 is a partial enlarged view taken from circle 10 in FIG. 2.

The dash-dash broken lines in the drawings depict the portions of the battery pack which form no part of the claimed design.

The dot-dash broken lines in the drawings depict the boundaries of the partial enlarged views that form no part of the claimed design.

1 Claim, 10 Drawing Sheets
